UNITED STATES PATENT OFFICE

2,489,402

OPERATING LEVER MEANS FOR
ROTARY BARS

George E. Dath, Mokena, Ill., assignor to W. H. Miner, Inc., Chicago, Ill., a corporation of Delaware

Application January 13, 1947, Serial No. 721,709

3 Claims. (Cl. 287—52.02.)

1.

This invention relates to improvements in operating lever means for rotary bars of door fasteners.

One object of the invention is to provide operating lever means of simple and rugged design for door fasteners of the rotary bar type employing a tubular operating bar having an operating lever handle fixed thereto for rotating the same, wherein the lever is secured to the bar by a welded connection, designed and constructed in such a manner as to relieve the welded joint of the connection of torsional strain to which the parts are subjected in effecting rotation of the operating bar in forcing the doors open or closed.

Other objects of the invention will more clearly appear from the description and claims herein-after following.

In the accompanying drawing forming a part of this specification, Figure 1 is an end elevational view of the body of an automobile truck provided with hinged doors and a rotary type of door fastener, illustrating my improvements in connection therewith. Figure 2 is an enlarged broken view of the mid portion of the right hand door, as illustrated in Figure 1, showing a portion of the rotary operating bar of the door fastener and the operating handle lever for the bar. Figure 3 is a horizontal sectional view, on an enlarged scale, corresponding substantially to the line 3—3 of Figure 1. Figure 4 is a vertical sectional view, corresponding substantially to the line 4—4 of Figure 3.

In said drawing, 10 indicates the end wall of the body of an automobile truck, provided with the usual door opening 11, closed by hinged doors 12 and 13. The door 12, the inner edge of which overlaps the inner edge of the door 13 in the closed position of the doors, has the door fastener 14 mounted thereon. The door fastener 14, which is indicated in dotted lines, is of the rotary bar type, which is well-known in this art, and comprises the usual rotary bar provided with keeper engaging means at opposite ends engaging with fixed keepers mounted on the body of the automobile truck above and below the door 12.

In carrying out my invention, I provide broadly a hollow tubular bar A which forms the rotary bar member of the door fastener, and an operating handle lever B fixed to the bar A for effecting rotation thereof in forcing the door 12 open or closed.

The tubular bar A is of circular cross section and has the operating handle lever B secured thereto at a point between the upper and lower

ends of the bar, the handle lever B being located so as to swing into a pocket 15 provided at the outer side of the door 12 when the door is forced to closed position by the door fastener.

5 The handle lever B is in the form of an elongated arm having a hand grip portion 16 at its outer end. The arm of the lever B, inwardly of the hand grip portion 16, is of channel-shaped, transverse section, having a lengthwise extending, vertical web 17, provided with laterally outwardly projecting, top and bottom flanges 18 and 19, which extend lengthwise. At the inner end of the channel-shaped arm portion, the lever B is provided with an arc-shaped wall portion 20, 10 which is a continuation of the web 17 and fits the curved outer surface of the tubular bar A and extends partly around said bar. The wall 20 terminates in a hook portion 21, which is engaged within and extends through an opening 22 provided in the wall of the tubular bar A. The end of the hook portion 21 is bent outwardly to provide a lip 23, which engages the inner side of the wall of the tubular bar A, beyond the opening 22. The inner end portion of the lever B is welded 15 to the tubular bar A at two zones, as indicated at 24 and 25, the welded joint 24 being made by filling in welding metal between the outer side of the bar and the inner side of the handle lever at the point where the arc-shaped wall portion 20 20 merges with the web 17 of the handle lever, and the welded joint 25 being made by filling in welding metal in the opening 22 of the tubular bar A between the wall of the opening 22 and the outer side of that portion of the hook of the lever B which extends through said opening. The lever 25 is thus firmly secured to the bar A.

As will be evident, the hooked connection of the lever B of the bar A serves to greatly reduce the strain on the welded joint between the lever 40 and the bar, due to the shouldered engagement between the lever and the bar at the hooked connection thereof when the lever is swung to rotate the bar in either clockwise or contra-clockwise direction, as viewed in Figure 3, the lip 45 23 of the hook of the lever acting as a fulcrum element to force the arc-shaped wall 23 into gripping contact with the outer side of the bar when the lever is swung inwardly toward the door to rotate the bar in contra-clockwise direction, 50 forcing the door closed.

I claim:

1. In a device of the character described, the combination with a rotatable hollow tubular bar; of an operating handle lever for rotating said bar, said lever having the inner end portion

thereof partly surrounding said bar; a hooked extension at the extremity of said surrounding inner end portion engaged through an opening in said bar; and a welded connection between said lever and said bar at said inner end portion of the lever.

2. In a device of the character described, the combination with a rotatable hollow tubular bar; of an operating lever having an arc-shaped wall at its inner end extending from said lever and 10 partly surrounding said bar; a hook at the outer end of said wall engaged through an opening in the wall of said bar; a lip at the extremity of said hook engaged with the inner side of the wall of said tubular bar at a point beyond the opening through which the hook extends; and a welded connection between said lever and bar at the inner end portion of the lever.

3. In a device of the character described, the combination with a rotatable hollow tubular bar; 15 of an operating lever having an arc-shaped wall of an operating lever having an arc-shaped wall at its inner end extending from said lever and

partly surrounding said bar; a hook at the outer end of said wall engaged through an opening in the wall of said bar; a lip at the extremity of said hook engaged with the inner side of the wall of said tubular bar at a point beyond the opening through which the hook extends; a welded connection between said lever and bar between one of the walls of the opening of said bar and the hook of the lever; and a second welded connection between said lever and bar at the rear side of said lever at the inner end of the arc-shaped wall of the latter.
